UNITED STATES PATENT OFFICE.

JOHN J. GROMME, OF LANCASTER, OHIO, ASSIGNOR TO THE HOCKING VALLEY MANUFACTURING COMPANY, OF SAME PLACE.

DESIGN FOR A FEED-CUTTER FRAME.

SPECIFICATION forming part of Design No. 24,317, dated May 14, 1895.

Application filed August 16, 1894. Serial No. 520,527. Term of patent 14 years.

To all whom it may concern:

Be it known that I, JOHN J. GROMME, a citizen of the United States, residing at Lancaster, in the county of Fairfield and State of 5 Ohio, have invented and produced a new and original Design for Feed-Cutter Frames, of which the following is a specification, reference being had to the accompanying drawing, showing the same.

10 The figure is a perspective view of a feed-cutter frame embracing my novel design, this one view being deemed sufficient to fully illustrate my design.

15 The leading features of my design consist in the divergence of the side rails from the rear upright of the frame and then curving inward near their forward ends to bring them parallel and at right angles to the cross rail at their juncture with the front uprights; and 20 also in the application of the rear upright or leg, B, at the apex of the side rails and the front uprights or legs D, to the opposite corners.

A are the two side rails proceeding from an apex at the rear upright B, horizontally and 25 diverging to the points a opposite each other where they are curved inward and proceed forward parallel to each other and are joined at right angles to the cross rail C, and to the front uprights D, thus presenting to the eye 30 a pleasing contour resembling somewhat that of the outline of a shield. The uprights B. and D, extend down vertically from the three corners of the shield.

Having described my design, what I claim 35 is—

The design for a feed cutter frame substantially as shown and described.

In testimony whereof I have hereunto set my hand this 14th day of August, A. D. 1894. 40

JOHN J. GROMME.
